C. S. CHOY

DISPENSING APPARATUS

Filed May 28, 1927

Inventor

Chee Shing Choy,

By Clarence A. O'Brien, Attorney

UNITED STATES PATENT OFFICE.

CHEE SHING CHOY, OF CHICAGO, ILLINOIS.

DISPENSING APPARATUS.

Application filed May 28, 1927. Serial No. 195,043.

The present invention relates to a dispensing apparatus and more particularly to a device for dispensing sugar in a sanitary manner.

5 An important object of the invention resides in the provision of apparatus whereby upon a single operation, a predetermined amount of sugar may be dispensed.

Another important object of the invention 10 resides in the provision of an apparatus of this nature having a spout formed with a compartment, said compartment having a valve at the upper end and a valve at the lower end and means for closing the first or 15 upper valve before the second or lower valve is opened.

A still further object of the invention resides in the provision of a device of this 20 nature which is simple in its construction, thoroughly efficient and reliable in its operation, and otherwise well adapted to the purpose for which it is designed.

With the above and numerous other objects in view, as will appear as the description 25 proceeds, the invention resides in certain novel details of construction, and in the combination and arrangement of parts as will be hereinafter more fully described and claimed.

30 In the drawing:

Figure 1 is a vertical section through the apparatus, taken substantially on the line 1—1 of Figure 2.

Figure 2 is a horizontal section taken substantially on the line 2—2 of Figure 1.

Figure 3 is a bottom plan view of the dispensing end of the spout.

Figure 4 is a sectional view, showing one 40 of the valves or closures.

Figure 5 is a detail view of one of the operating members, and

Figure 6 is a detail view of a rocker.

Referring to the drawing in detail, it will be seen that the numeral 5 denotes a 45 container, the upper portion 6 of which is of a frusto-conical formation and has a lid 7 closing the upper end thereof. A spout 8 is formed on the tapered or upper portion 6 and has a partition 9 formed in its lower portion. This partition 9 is provided with an opening 10. A gate closure 11 is hingedly mounted on the lower extremity of the spout as at 12. A casing 13 is formed in the spout and has longitudinally extending slots 14. A second housing 15 is formed 55 within the spout and the tapered portion 6

of the container and encases a portion of the housing 13. A rod 16 has its lower end bifurcated, the furcations 17 being L-shaped and terminating in inwardly directed ends 18. These furcations project through slots 14 and the ends 18 engage with apertured ears or lugs 19 on the gate closure 11. The rod is slidable through an opening in the upper end of the housing 13. A spring 20 is attached to the rod and to the end of the casing 13 and normally holds the rod so that the gate closure 11 is normally closed.

A sleeve 22 projects inwardly from the upper part of the portion 6. A tube 23 is 70 slidable through the sleeve 22 and has a knob 24 on the outer end thereof. The inner end of the tube 23 is enlarged as is indicated at 25. A spring 26 is disposed about the sleeve 22 having one end attached 75 to the portion 6 and another end attached to the tube 23 for normally holding the tube outwardly. The upper end of the rod 16 projects into the tube 23 and terminates normally a spaced distance from the knob 24.

A rocker R comprises a transverse intermediate tubular portion 28, through which projects a pin 29 to pivot the rocker in the housing 15. One arm of the rocker is in the form of a plate 30 having an 80 oblong slot 31 therein, through which projects the tube 23, the enlargement 25 being too large to pass through this slot 31. The other arm of the rocker is shown at 32, and is pivotally engaged as at 34, to a rod 35, 85 which is slidable through an opening in the bottom of the housing 15 and has a plurality of diverging branches 36 projecting through openings 10 and attached to a disc closure 37 for closing the openings 10. A 90 spring 38 is engaged with the rod 16 and with the extremity of the arm 30 and normally holds the rocker R so that the valve 37 will be closed when the tube 23 is moved 95 inwardly. However, the spring 26 is stronger than the spring 30, so that the tube is normally held outwardly and the abutment rocks the rocker R so that the spring 38 is normally under tension.

The container 5 is filled by removing the 105 lid 7. After the lid has been replaced, and it is desired to dispense sugar from the device, the same will be tilted to tend to pour its contents through the spout 8, into the desired receptacle. When thus disposed the 110 tube 23 is forced inwardly by the thumb engaging the knob 24. The movement of the

tube 23 allows the spring 38 to rock the rocker R and close the valve 37 over the openings 10. Further movement of the tube 23 causes the knob 24 to abut the end of the 5 rod 16 and to open the gate valve 11. In this operation it will be seen that the sugar which flows through the openings 10 and fills the compartment below the partition 9 will be of a predetermined amount and will 10 be dispensed from the spout upon the opening of the escape valve 11, and while the gate valve 11 is opened, no further sugar may flow through the openings 10.

It is thought that the construction, operation and advantages of this invention will 15 now be quite apparent to those skilled in this art, without a more detailed description thereof. The present embodiment of the invention has been disclosed in detail, 20 merely by way of example, since in actual practice it attains the features of advantage enumerated as desirable in the statement of the invention and the above description. It will be apparent that changes in the details 25 of construction, and in the combination and arrangement of parts may be resorted to without departing from the spirit and scope of the invention as hereinafter claimed or sacrificing any of its advantages.

Having thus described my invention, what 30 I claim as new is:

1. A device of the class described comprising a container, a spout formed in the container, a partition extending across the 35 spout and formed with an opening, a gate valve hinged on the extremity of the spout, a housing formed in the spout and having slots in its sides, a rod slidable through the inner end of the housing and having a bifurcated end, the furcations of which are movable through the slot, the extremities of the furcations being engaged with the gate valve, a sleeve extending inwardly of the 40 container, a tube slidable through the sleeve, a knob on the outer end of the tube, a rocker mounted in the container, a housing about the rocker, one arm of the rocker being formed with a slot through which 45 the tube extends, the inner end of said tube being enlarged and incapable of passing through the slot, a spring engaged with said arm of the rocker and with the rod, a second rod pivotally engaged with the other arm of the rocker and slidable through the second housing and through the opening of the partition, a valve on the rod to close the opening in the partition, a spring about the sleeve being fixed to the container and having an end fixed to the tube, a spring about the first rod within the first housing having one end fixed to the housing and one end fixed to the rod for normally maintaining said rod to close the gate 50 valve.

said tube extends, the inner end of said tube being enlarged and incapable of passing 50 through the slot, a spring engaged with said arm of the rocker and with the rod, a second rod pivotally engaged with the other arm of the rocker and slidable through the second housing and through the opening of the partition, a valve on the rod to close the opening in the partition, a spring about the sleeve being fixed to the container and having an end fixed to the tube.

2. A device of the class described comprising a container, a spout formed in the container, a partition extending across the spout and formed with an opening, a gate valve hinged on the extremity of the spout, a housing formed in the spout and having slots in its sides, a rod slidable through the inner end of the housing and having a bifurcated end, the furcations of which are movable through the slot, the extremities of the furcations being engaged with the gate valve, a sleeve extending inwardly of the container, a tube slidable through the sleeve, a knob on the outer end of the tube, a rocker mounted in the container, a housing about the rocker, one arm of the rocker being formed with a slot 65 through which said tube extends, the inner end of said tube being enlarged and incapable of passing through the slot, a spring engaged with said arm of the rocker and with the rod, a second rod pivotally engaged with the other arm of the rocker and slidable through the second housing and through the opening of the partition, a valve on the rod to close the opening in the partition, a spring about the sleeve being fixed to the container and having an end fixed to the tube, a spring about the first rod within the first housing having one end fixed to the housing and one end fixed to the rod for normally maintaining said rod to close the gate 70 valve.

In testimony whereof I affix my signature.

CHEE SHING CHOY.
